OTHER PUBLICATIONS

Preinterview First Office Action received for U.S. Appl. No. 16/398,145 dated Jan. 30, 2020, 32 pages.

(Continued)

Primary Examiner — Daniel J Domino(74) *Attorney, Agent, or Firm* — FisherBroyles, LLP(57) **CLAIM**

The ornamental design for a display device or portion thereof with graphical user interface, as shown and described.

DESCRIPTION

This application claims the benefit of U.S. application Ser. No. 16/398,145, filed 29 Apr. 2019, U.S. application Ser. No. 16/398,148, filed Apr. 29, 2019, the disclosure of each of which is incorporated, in its entirety, by this reference.

The FIGURE is a front view of a display device with graphical user interface.

The broken lines showing portions of the display device or graphical user interface illustrate portions of the article, and form no part of the claimed design.
